UNITED STATES PATENT OFFICE.

JOHN P. COLEMAN, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROL APPARATUS.

1,230,868.

Specification of Letters Patent. Patented June 26, 1917.

Application filed October 12, 1915. Serial No. 55,498.

To all whom it may concern:

Be it known that I, JOHN P. COLEMAN, a citizen of the United States, residing at Edgewood borough, in the county of Allegheny and State of Pennsylvania, have invented certain new and useful Improvements in Railway-Traffic-Control Apparatus of which the following is a specification.

My invention relates to railway traffic

control apparatus and more particularly it relates to apparatus for causing reverse movements of railway switches and the like,

One object of my invention is to render impossible the operation of a railway switch if the lock rod thereof is removed.

I will describe one form of apparatus embodying my invention and then point out the novel features thereof in claims.

In the accompanying drawings, Figure 1 is a view showing one form of control apparatus embodying my invention applied to a railway switch. Fig. 2 is a view showing a horizontal section of the apparatus shown in Fig. 1. Figs. 3, 4, and 5 are views showing vertical sections through Fig. 2 on lines III—III, IV—IV, and V—V, respectively looking in the directions of the arrows. Fig. 6 is a plan view of part of the switch operating rod 4.

Similar reference characters refer to similar parts in each of the several views.

Referring first to Fig. 1, reference character A designates one form of switch operating and locking mechanism, which is described in my co-pending application Serial No. 28,840, filed May 18, 1915 for railway traffic control apparatus. Mechanism A is fixed by suitable bolts 21 and 22 to ties 23 and 24 (see also Fig. 3). The switch operating rod, designated 4, is connected by a bracket 8 and a tie rod 9 to the switch points 11 of which only one is shown in the drawing. The switch is shown in what I shall term its normal position; it is thrown into the reversed position, *i. e.*, a position in which switch point 11 closes against the stock rail 12 by means of rod 4, which is operated by mechanism A as I shall describe hereinafter. A lock rod 13 is connected to the switch points and constrained to move therewith by means of a bracket 18 and a tie rod 17. Mechanism A is adapted to lock the rod 4 as I shall describe hereinafter, so that

the switch is rigidly held in either of its normal or reversed positions. Reference character B designates a casing containing a circuit controller for controlling the so-called indication circuits of the switch. One such circuit controller and one form and arrangement of indication circuits are shown and described in my co-pending application above identified.

With reference now to Figs. 1 to 5, mechanism A comprises castings 1, 2 and 3 bolted together by bolts 26 and 27. Casting 1 comprises cylinders 1^a and 1^b and casting 2 comprises cylindrical guides 2^a and 2^b, which are so designed that, when the castings are bolted together, cylinders 1^a and 1^b are co-lineal respectively with guides 2^a and 2^b. Pistons 31^a and 31^b are fitted air tight in cylinders 1^a and 1^b respectively by means of piston rings 32. A rack 33^a is secured at one end to piston 31^a and at the other end to a plunger 34^a adapted to reciprocate in guide 2^a. A similar rack 33^b is fixed in like manner to piston 31^b and a plunger 34^b in guide 2^b. The toothed surfaces of the racks engage opposite sides of a pinion 36 which is securely mounted on a crank shaft 37. Rollers 41 mounted on trunnions 78 screwed into casting 2 form lateral guides for racks 33^a and 33^b for the purpose of preventing rotation of the racks on the axis of the cylinders and in order to maintain the proper relation of the pitch lines of the racks and the pinion. As thus far described it is plain that admission of compressed air into cylinder 1^a through a pipe 48^a will cause rack 33^a to move to the right (as viewed in Fig. 2) so that pinion 36 is turned counter-clockwise and draws rack 33^b to the left. If thereupon air is admitted to cylinder 1^b through a pipe 48^b the reverse movement occurs. The rotation of pinion 36 and crank shaft 37 is utilized to operate the switch in the following manner: As shown in Figs. 3 and 5, shaft 37 is provided at its lower end with a crank arm 46. A crank pin 44 on the underside of crank arm 46 is adapted to slide in a transverse groove 82 in rod 4 (see also Fig. 6). Rod 4 is mounted in slide bearings 83 in casting 2, so that the rod is constrained to a reciprocal motion in the direction of its axis. From Fig. 6 it is apparent that circu-

lar motion of crank pin 44 in the direction of the arrow from the position marked *a* to the position marked *d* causes rod 4 to move to the left through the straight line distance between positions *a* and *d*. By proper proportioning of pinion diameter to length of piston stroke the crank shaft is turned counter-clockwise through the angle from *a* to *d* when piston 31^a is pushed through its entire stroke in piston 1^a by air pressure from pipe 48^a; conversely, the crank shaft is turned clockwise from *d* to *a* when piston 31^b is moved through its entire stroke from left to right by air pressure from pipe 48^b. The linear distance from *d* to *a* (Fig. 6) is equal to the throw of the switch, so that a complete operation of the above described mechanism causes a complete movement of the switch from one position to the other according as the movement of the mechanism is in one direction or the other.

The locking of the switch in one extreme position or the other is accomplished by means of plungers 34^a and 34^b which engage corresponding recesses in the lock rod. As shown in Figs. 3 and 4, the lock rod comprises a lower rod 13 which is connected to the switch points and an upper rod 13^c parallel to the lower rod and attached thereto by means of an adjustable bracket 100. Thus the two rods are constrained to move as a unit in slide bearings in casting 3. When the mechanism is in the position shown in the drawings, a shoulder 51^b on the lower side of plunger 34^b enters a notch or recess 93 in the upper side of rod 13, so that longitudinal movement of the lock rod is prevented. In other words, rod 13 and therefore the switch are securely locked in position. Naturally, when the switch is to be reversed it must first be unlocked by the withdrawal of shoulder 51^b of plunger 34^b from notch 93. This occurs during the first part of the movement of the mechanism, while rack 33^b (Fig. 2) is being drawn to the left by the rotation of pinion 36. During this time crank pin 44 moves from its initial position *a* in Fig. 6 to the position marked *b*. This motion is practically at right angles to the longitudinal axis of rod 4, so that due to a slight amount of clearance, the switch points remain undisturbed. The switch is now unlocked and ready to be reversed. This occurs while the crank pin moves from *b* to *c* (Fig. 6) in the direction of the arrow. During this time operating rod 4 is drawn to the left (Fig. 6) by means of crank pin 44, as explained hereinbefore, so that the switch points are shifted from the position shown in Fig. 1 to the reversed position. Lock rod 13, being connected to the switch points, is pushed to the left (Fig. 4), by the movement of the switch points, until when the switch is fully reversed, *i. e.*, when the crank pin has arrived at *c* (Fig.

6), a notch 92 in upper rod 13^c comes into alignment with plunger 34^a in cylinder 2^a. By this time plunger 34^a has advanced to the right (in Fig. 2) to the end of guide 2^a. Further advance causes a shoulder 51^a on the upper side of the plunger to enter notch 92 of rod 13^c, thereby locking the switch securely in its new position. During this stroke of plunger 34^a, pinion 36 turns crank pin 44 from *c* to *d* (Fig. 6). This movement is again at right angles to the axis of rod 4 and does not cause any appreciable movement of the switch points. A reverse movement of the mechanism is similar and need therefore not be explained.

The mechanism as thus far described, not only locks the switch points in one or the other position after they have been moved there, but also prevents a completion of the operation of the mechanism if the switch does not fully respond to the movement of the mechanism. To illustrate, suppose that during the above operation, rod 4 were broken or otherwise disconnected from the switch. The switch points then would either not have moved at all or would have moved only through a portion of the full stroke. At any rate, notch 92 of lock rod 13^c would not have been moved far enough to get into alignment with plunger 34^a, so that shoulder 51^a would have encountered the side of rod 13^c and would thus have prevented further movement of the mechanism. This would have been brought to the notice of the switch operator by means of the indication circuits, as is readily understood by those versed in the art.

By the present invention, I provide a device whereby the full operation of the mechanism is prevented if the lock rod is removed—no matter whether or not the switch has fully responded to the movement of the mechanism. To this end I provide levers 101 and 102 (see Figs. 3 and 4) hinged on the shanks of pivot screws 104 fixed in casting 3 respectively above rod 13^c and below rod 13. Springs 103 are riveted to the casting and exert pressure on the levers so that they bear respectively against the upper side of rod 13^c and the lower side of rod 13, as shown in the full line positions on the drawing. If lock rod 13^c were withdrawn from the mechanism, spring 103 would press lever 101 into the dotted position shown on the drawing in which the underside of the lever would rest against member 105 of casting 3. The head 106 of lever 101 would then be in the path of shoulder 51^a on plunger 34^a so that if a complete operation of the mechanism as described above were attempted, the movement could not be completed because shoulder 51^a of plunger 34^a would encounter head 106 of lever 101 as the plunger would be about to enter casting 3. Similarly, if rod 13 were

withdrawn, lever 102 would be swung by means of spring 103 into the dotted position wherein its head 106 would obstruct plunger 34^b, so that, if the mechanism were in the 5 reversed position and a switch movement in the opposite direction were attempted, the operation of the mechanism could not be completed because shoulder 51^b of plunger 34^b would encounter head 106 as the plunger 10 would be about to enter casting 3. As noted above, the indication system would in a suitable manner notify the switch operator of the incompleteness of the switch movement, so that steps would be taken to prevent train 15 movements over the switch until the lock rod had been restored to the mechanism.

Although I have herein shown and described only one form of apparatus embodying my invention, it is understood that various 20 changes and modifications may be made therein within the scope of the appended claims without departing from the spirit and scope of my invention.

Having thus described my invention, what 25 I claim is:

1. In a switch locking mechanism the combination of a lock rod, a plunger for locking said rod, and means for obstructing said plunger when said lock rod is withdrawn 30 from the mechanism.

2. In a switch locking mechanism the combination of a lock rod, a plunger for locking said rod, and means biased to obstruct said plunger when said lock rod is withdrawn 35 from the mechanism.

3. In a switch locking mechanism the combination of a lock rod, a plunger for locking said rod, and a pivotally mounted member for obstructing said plunger when said 40 lock rod is withdrawn from the mechanism.

4. In combination, a switch operating mechanism, a lock rod adapted to be locked by said mechanism, and means for preventing a complete operation of said mechanism 45 when said lock rod is withdrawn from said mechanism.

5. In combination, a switch operating mechanism, a member movable therewith, a lock rod adapted to be locked by said member, and means for obstructing the movement of said member when said lock rod is withdrawn from said mechanism.

6. In combination, a switch, mechanism for moving said switch, a plunger movable with said mechanism, a rod connected to said switch adapted to obstruct the movement of said plunger, a recess in said rod for receiving said plunger, and means for obstructing the movement of said plunger when said rod 60 is withdrawn.

7. In combination, a switch, mechanism for moving said switch, a plunger movable with said mechanism, a rod connected to said switch adapted to obstruct the movement of said plunger, a recess in said rod

for receiving said plunger, and a member biased to obstruct the movement of said plunger when said rod is withdrawn.

8. In combination, a switch, mechanism for moving said switch, a plunger movable with said mechanism, a rod connected to said switch adapted to obstruct the movement of said plunger, a recess in said rod for receiving said plunger, a member, and means for biasing said member against said rod in 70 order to obstruct said plunger when said rod is withdrawn from said mechanism. 75

9. In combination, a switch, mechanism for moving said switch, a plunger movable with said mechanism, a rod connected to 80 said switch adapted to obstruct the movement of said plunger, a recess in said rod for receiving said plunger, and a pivotally mounted member adapted to bear against said rod in order to obstruct said plunger when said rod is withdrawn from said mechanism. 85

10. In combination, a pinion, a rack co-acting with said pinion, a switch, means operated by said pinion for moving said 90 switch, a lock rod connected to said switch, means for locking said rod by said rack, and means for obstructing the movement of said rack when said lock rod is withdrawn.

11. In combination, a pinion, a rack co-acting with said pinion, a switch, means operated by said pinion for moving said 95 switch, a plunger on said rack, a lock rod connected to said switch adapted to obstruct the full movement of said plunger except 100 when said switch has responded to said pinion, and a member for obstructing the full movement of said plunger when said lock rod is withdrawn.

12. In combination, a pinion, two racks 105 meshing with said pinion, a switch, means controlled by the pinion for moving the switch, a lock rod for the switch, means controlled by the movement of said racks for locking said lock rod in normal or reversed 110 position, and means for preventing a full movement of said racks when said lock rod is withdrawn.

13. In combination, a pinion, two racks meshing with said pinion, a switch, means 115 controlled by the pinion for moving said switch, a lock rod for the switch adapted to obstruct the full movement of said racks, recesses in said lock rod for allowing a full movement of said racks, and means for preventing a full movement of said racks when said lock rod is withdrawn.

14. In combination, a pinion, two racks meshing with said pinion, a switch, means controlled by the pinion for moving said 120 switch, plungers controlled by said racks, a lock rod for the switch, recesses in said lock rod for receiving said plungers, and means for obstructing said plungers when said lock rod is withdrawn. 125

130

15. In combination, a railway switch, mechanism for moving said switch, locking apparatus associated with said switch and said mechanism for locking said switch and 5 for preventing completion of a movement of said mechanism if the locking is not effected, and means controlled by said locking apparatus for preventing completion of the movement of the mechanism in the event of the 10 displacement of a part of said apparatus to

such extent that the movement of the mechanism could otherwise be completed without locking the switch.

In testimony whereof I affix my signature in presence of two witnesses.

JOHN P. COLEMAN.
